SCARF

Vera Neumann, Ossining, N. Y.

Application June 9, 1952, Serial No. 20,095

Term of patent 7 years

(Cl. D3—12)

To all whom it may concern:

Be it known that I, Vera Neumann, a citizen of the United States of America and a resident of Ossining, Westchester County, State of New York, have invented a new, original, and ornamental Design for a Scarf, of which the following is a specification, reference being had to the accompanying drawing, forming a part hereof, showing a plan view of the obverse side of a scarf showing my new design, the reverse side being identical therewith.

I claim:

The ornamental design for a scarf, substantially as shown and described.

VERA NEUMANN.
